(57) **CLAIM**

(51) **LOC (9) Cl.** **12-11**

The ornamental design for a handle grip for two-wheeled motor vehicle, as shown and described.

(52) **U.S. Cl.** **D8/303**

DESCRIPTION

(58) **Field of Classification Search** D8/303,

D8/300, 70; D12/110, 111, 178; 16/110.1,
16/421, 430, 111.1, DIG. 12; 74/488, 489,
74/502.2, 551.1-551.9, 557; 180/219, 220;
219/201, 202, 204, 494, 497, 504, 506, 530,
219/540, 544

See application file for complete search history.

(56) **References Cited**

FIG. 1 is a front perspective view from above of a handle grip for two-wheeled motor vehicle, showing my new design, which includes a switch for actuating an inner grip heater and a handle grip;
FIG. 2 is a front view thereof;
FIG. 3 is a rear view thereof;
FIG. 4 is a top plan view thereof;
FIG. 5 is a bottom plan view thereof;
FIG. 6 is a left side view thereof; and,
FIG. 7 is a right side view thereof.
